[57] CLAIM

The ornamental design for an ornament, substantially as shown and described.

DESCRIPTION

FIG. 1 is a front perspective view of an ornament showing my new design;

FIG. 2 is a front elevational view thereof;

FIG. 3 is a rear elevational view thereof;

FIG. 4 is an elevational view of the top thereof, the same being identical to an elevational view of the bottom thereof;

FIG. 5 is an elevational view of the right side thereof, the same being identical to an elevational view of the left side thereof.

FIG. 1**FIG. 4****FIG. 2****FIG. 3****FIG. 5**
